UNITED STATES PATENT OFFICE.

ULYSSES S. HUGGINS, OF WELLSBURG, WEST VIRGINIA, ASSIGNOR OF ONE-HALF TO WILLIAM E. RATCLIFFE, OF SAME PLACE.

PILLOW-SHAM HOLDER.

SPECIFICATION forming part of Letters Patent No. 623,719, dated April 25, 1899.

Application filed September 23, 1898. Serial No. 691,716. (No model.)

To all whom it may concern:

Be it known that I, ULYSSES S. HUGGINS, a citizen of the United States, residing at Wellsburg, in the county of Brooke, State of West Virginia, have invented certain new and useful Improvements in Pillow-Sham Holders, of which the following is a specification, reference being had therein to the accompanying drawings.

10 This invention relates to a pillow-sham holder, and particularly to a holder of the class embodying a supporting-pole extending the length of the head portion of the bedstead.

The invention has for its object to provide 15 an improved construction of bracket for supporting a pole, which bracket may be reversed and applied to either side of the bedstead.

A further object is the construction of caps or ferrules placed upon the opposite ends of 20 the pole and resting within the bracket.

The invention has for its object also to provide a novel means for attaching the pillow-sham to the supporting-wires carried by the pole.

25 Other objects and advantages of the invention will hereinafter appear, and the novel features thereof will be particularly pointed out in the appended claims.

In the drawings, Figure 1 is a perspective 30 of the invention. Fig. 2 is a similar view of the pole and end ferrules. Fig. 3 is an end view. Fig. 4 is a vertical section through the ferrule at the left of Fig. 1, with the parts in an opposite position; and Figs. 5, 6, and 7 are 35 detail perspectives showing the several adjusted positions of the holder with and without the sham applied thereto.

Like letters of reference indicate like parts 40 throughout the several figures of the drawings.

The letter A designates a pole, which may be formed of any desired material, preferably of wood, and through which the ends of a sham-supporting frame A' are passed. These 45 ends are bent at an angle to the body, as at A², to form a loop for the reception of a tape A³ or other suitable material, to which the sham may be pinned or otherwise attached. Upon the opposite ends of this pole ferrules 50 or caps B and B' are applied, the former of

which is provided at its end with a segmental bearing-surface B² and locking-point B³. The opposite ferrule B' is provided with a bearing-surface B⁴, extending entirely around the same. Coöoperating with these ferrules and secured to the opposite sides of the bedstead are brackets C, each of which is similar in construction, so that they may be reversed in position or applied to a bedstead by an unskilled person. The ends of these brackets 60 are formed with a recessed head C', having therein an annular bearing-surface, and at the upper and lower portion thereof with oppositely-located recesses or depressions C². These recesses are adapted to receive the locking-point B³, carried by the ferrule B, and thus retain the holder in an elevated position, as illustrated in Fig. 7. The segmental portion of the ferrule B will move upon the annular face of the recessed head C' until the 65 locking-point B³ reaches a position opposite the lower notch C², and will then drop and rest within the same.

For the purpose of assisting in retaining the ferrules within the sockets and clamping 70 the parts in close contact screw-eyes D are provided, which pass through elongated slots C³, formed in the heads C', and are passed through the ferrules into the pole. These 75 form a convenient operating-handle for the pole, and when screwed into position draw the ferrule into contact with the bracket. By lifting the screw-eye entering the ferrule B the locking-point may be lifted from the recess and the holder lowered into the position 80 shown in Figs. 5 and 6. The opposite ferrule B', having a complete segmental surface, simply rotates within the bracket at that end.

The operation of the parts will be apparent 85 from the foregoing description; but the particular object of the invention is to provide a structure by which the pole may be reversed in position and operated from either side of the bedstead. This is essential, as in a great 90 many cases one side of the bedstead rests against the wall, in which event the pole is simply reversed to bring the ferrule B to the side of the bedstead most convenient of access. The provision of the oppositely-located recesses in the brackets C permits the same to 95 100

be applied in proper position at either side of the bedstead, so that the parts can be assembled for use by any person. Whenever the position of the bedstead is moved within a room, the pole can be readily reversed to operate the sham from the most convenient side, and the construction of bracket screw-eye for retaining the parts together prevents any accidental displacement of the parts and effectually retains the same in operative relation. The simplicity of the bracket permits the same to be stamped from light metal, and the ferrules are similarly formed, so that the parts are far less expensive than were it necessary to provide castings for the same.

Having described my invention, what I claim as new, and desire to secure by Letters Patent, is—

1. A pillow-sham holder comprising a pole provided at one end with a bearing and at the opposite end with a locking-point, oppositely-located brackets having bearing-surfaces adapted to receive the ends of said pole, each of which is provided with opposite lock-

ing-recesses and an elongated aperture, and an operating-handle passing through said aperture and into said pole; substantially as specified.

2. A pillow-sham holder comprising a pole, a ferrule at one end thereof provided with a continuous bearing-surface, a ferrule at the opposite end of said pole provided with a peripheral bearing and with a locking-point, bearing-brackets adapted to receive said ferrules, each of which is provided with opposite locking-recesses and elongated slot in its head, attaching and operating devices passed through said brackets and ferrules, and a supporting-frame having its ends passed through said pole and angularly bent to provide an attaching-loop for a sham; substantially as specified.

In testimony whereof I affix my signature in presence of two witnesses.

ULYSSES S. HUGGINS.
